J. POKORNY,

WINDOW AWNING.

APPLICATION FILED APR. 25, 1919.

1,332,752.

Patented Mar. 2, 1920.

UNITED STATES PATENT OFFICE.

JOSEPH POKORNY, OF ST. LOUIS, MISSOURI, ASSIGNOR TO MAY DEPARTMENT STORES COMPANY, OF ST. LOUIS, MISSOURI, A CORPORATION OF NEW YORK.

WINDOW-AWNING.

1,332,752.

Specification of Letters Patent.

Patented Mar. 2, 1920.

Application filed April 25, 1919. Serial No. 292,556.

To all whom it may concern:

Be it known that I, JOSEPH POKORNY, a citizen of the United States, residing at St. Louis, Missouri, have invented a certain new 5 and useful Improvement in Window-Awnings, of which the following is a full, clear, and exact description, such as will enable others skilled in the art to which it appertains to make and use the same.

10 This invention relates to window awnings of the type which comprise a strip of canvas or other suitable fabric connected at its upper end to a spring roller and at its lower end to the cross piece of an extension member whose side arms are pivotally connected at their inner ends to sleeves which slide on vertically-disposed guide rods secured to the window frame, the upper portion of said strip of fabric being held in a vertical position 15 when the awning is open by means of a transversely-disposed bar or member arranged at approximately the center of the window opening and provided at its ends with sleeves which also slide on said vertically-disposed guide rods.

20 The object of my present invention is to provide an awning of the general type referred to, in which, the vertically-disposed guide rods on which the sleeves of the 25 transversely-disposed bar and the sleeves of the extension member are slidably mounted are equipped with stops that arrest the downward movement of said transversely-disposed bar, but which have no effect on 30 the vertical sliding movement of the sleeves to which the extension member is pivotally connected, thereby producing a window awning that is inexpensive to manufacture and install.

35 Figure 1 of the drawings is a front elevational view of a window awning constructed in accordance with my invention.

40 Fig. 2 is a vertical sectional view of said awning.

45 Fig. 3 is a vertical sectional view similar to Fig. 2, but illustrating the transversely-disposed bar and the extension member raised or in the position they occupy when the awning is closed or not in use; and

50 Fig. 4 is a perspective view, illustrating the operation of the stop on one of the guide rods that arrests the downward movement of the transversely-disposed bar.

55 Referring to the drawings which illustrate the preferred form of my invention,

A designates a strip of canvas or other suitable fabric whose upper end is connected to a spring roller B mounted in brackets 1 on the window frame adjacent the upper end of the window opening, said spring roller 60 being similar to the spring rollers now generally used for window shades and provided with a winding spring (not shown) that turns the roller in a direction to wind the fabric A onto same, and locking dogs (not 65 shown) for locking the roller and holding it against rotation. The lower end of the strip of fabric A is connected to the cross piece 2 of a yoke-shaped extension member whose side arms 3 are pivotally connected 70 at their inner ends to sleeves 4 which slide on vertically-disposed guide rods 5 arranged at the sides of the window opening, as shown in Fig. 1. When the awning is lowered or in use, as shown in Figs. 1 and 2, the strip 75 of fabric A passes under a transversely-disposed bar C arranged at the center of the window opening and mounted on the guide rods 5 in such a manner that it will be shifted upwardly into an inoperative position 80 adjacent the upper side of the window opening when the awning is closed, as shown in Fig. 3, said bar C serving to hold the upper portion of the fabric A in a substantially vertical position when the awning is 85 lowered or in use, as shown in Fig. 2. The spring roller B is adapted to be turned in a direction to trip the locking dogs of same or to unwind the fabric A from said roller by means of a tape 6, shown in dotted lines 90 in Fig. 2. If it is desired to raise the awning from its operative position shown in Fig. 2, into its inoperative position shown in Fig. 3 it is only necessary to pull downwardly on the tape 6 sufficiently to trip the 95 locking dogs of the roller B, and thus permit the spring of said roller to rotate the roller in a direction to wind the fabric A onto same, the upward pull that is exerted on said fabric causing the yoke-shaped extension member connected to the lower end of the fabric to swing upwardly on the sleeves 4 and then travel upwardly into the position shown in Fig. 3, the cross piece 2 of said extension member operating to move 100 the transversely-disposed bar C upwardly into its inoperative position. When it is desired to lower the awning it is only necessary to pull downwardly on the tape 6 so as to turn the roller B in the opposite direc- 105 110

tion and unwind the fabric A from the roller, the yoke-shaped extension member and the transversely-disposed bar C moving downwardly automatically into the position 5 shown in Figs. 1 and 2.

The transversely-disposed bar C is provided at its ends with sleeves 7 which slide on the guide rods 5 and said guide rods are provided with stops that arrest the downward movement of the transversely-disposed bar C, but which have no affect on the vertical movement of the extension member to which the lower end of the fabric A is connected. In the form of my invention 10 herein shown the stops just referred to are integrally connected to the guide rods 5 and are preferably formed by squeezing or pressing each of the guide rods 5 at a point intermediate the ends of same so as to 15 change the cross-sectional shape of the rod and thus form a flat portion 8 on same of sufficient width to prevent the sleeve 7 from sliding downwardly past said flat portion but not wide enough to interfere with the 20 vertical movement of the sleeve 4 upwardly or downwardly past said flat portion. As shown in Fig. 4, the sleeve 7 is approximately of the same internal diameter as the diameter of the rod 5. Consequently, the 25 upper end of the flat portion 8 on said rod will serve as a stop 8^a that limits the downward movement of the sleeve 7 connected to one end of the transversely-disposed bar C. The other sleeve 4 on said guide rod, to 30 which one of the side arms 3 of the extension member is connected, is made a trifle larger than the diameter of the flat portion 8 on the guide rod 5, so that said sleeve will travel freely past said flat portion. In the awning herein shown the transversely disposed bar C is pivotally connected to the sleeves 7 by means of pins 9 which pass through elongated slots 10 in the bar C, thereby permitting the bar C to 35 assume a slightly angular position without binding on the guide rods 5 and also permitting sufficient lateral play between the sleeves 7 and the bar C to compensate for any slight mal-alinement of the two guide rods 5 on the window frame. The guide rods 5 can be secured to the window frame in various ways without departing from the spirit of my invention, and if desired, the sleeves 7 to which the transverse bar C 40 is connected can be provided with forwardly-projecting lugs 11 that serve as abutments against which the cross piece 2 of the extension member strikes and moves the bar C upwardly during the operation of 45 raising the awning.

A window awning of the construction above described can be manufactured cheaply and installed quickly and easily, owing to the fact that it is not necessary to se-

cure stops to the window frame to arrest the downward movement of the transversely-disposed bar C. Furthermore, by equipping the guide rods 5 with integral stops for arresting the downward movement of said transversely-disposed bar C, I insure said bar C being arranged in a perfectly horizontal position when the awning is installed.

Having thus described my invention, what I claim as new and desire to secure by Letters Patent, is:

1. A window awning, comprising a strip of fabric, a roller to which the upper end of said fabric is connected, vertical guide rods arranged at the sides of the window opening, an extension member connected to the lower end of said strip of fabric and provided with sleeves that slide vertically on said guide rods, a transversely-disposed bar under which the fabric passes provided at its ends with sleeves that slide on said guide rods, and stops on said guide rods that arrest the downward movement of said transversely-disposed bar but which have no affect on the sliding movement of the sleeves on the extension member.

2. A window awning, comprising a strip of fabric, a roller to which the upper end of said fabric is connected, vertical guide rods arranged at the sides of the window opening, an extension member connected to the lower end of said strip of fabric and provided with sleeves that slide vertically on said guide rods, a transversely-disposed bar under which the fabric passes provided at its ends with sleeves that slide on said guide rods, and integral stops on said guide rods of such form and dimensions that the sleeves on the extension member can slide freely past same but being large enough to arrest the downward movement of the sleeves on said transversely-disposed bar.

3. A window awning, comprising a strip of fabric, a roller to which the upper end of said fabric is connected, guide rods arranged at the sides of the window opening, an extension member connected to the lower end portion of said strip of fabric and provided with pivotally connected sleeves that slide vertically on said guide rods, a transversely-disposed bar under which the fabric passes, sleeves on said guide rods joined to said bar by slot and pin connections, and an integral stop on each of said guide rods formed by squeezing or pressing said guide rod so as to change the cross-sectional shape of same, said stops being of such dimensions that they arrest the downward movement of the sleeves on the transversely-disposed bar but have no affect on the sliding movement of the sleeves connected to the extension member.

JOSEPH POKORNY.
